(57) **CLAIM**

The ornamental design for a lighting fixture, as shown and described.

DESCRIPTION

FIG. 1 is a perspective view of a lighting fixture showing the new design.

FIG. 2 is a front elevational view thereof, the rear elevational view, left side elevational view, and right side elevational view being identical to the front elevational view.

FIG. 3 is a bottom plan view thereof.

FIG. 4 is a top plan view thereof; and,

FIG. 5 is an end elevational view in section taken along line 5—5 in FIG. 2 with the internal parts omitted.

The portions shown by double cross-hatched lines in the end elevational view are transparent.
